(57) **CLAIM**

The ornamental design for “optical curing apparatus,” as shown and described.

DESCRIPTION

FIG. 1 is a perspective view of “optical curing apparatus” showing my new design thereof;

FIG. 2 is a right side elevational view thereof;

FIG. 3 is a top plan view thereof;

FIG. 4 is a front side elevational view thereof;

FIG. 5 is a bottom plan view thereof.;

FIG. 6 is a left side elevational view thereof; and,

FIG. 7 is a rear side elevational view thereof.
